ELECTRICAL SWITCH

Byron R. Criswell, Lake Forest, Ill., assignor to
 Zenith Radio Corporation, a corporation of
 Illinois

Application October 3, 1946, Serial No. 700,875

3 Claims. (Cl. 200—4)

1

This invention relates to tone control arrangements of the type particularly useful in small portable apparatus, such as wearable radios or hearing aids. In such small portable apparatus it is advantageous to minimize the number of controls to allow for ease of operation.

One way in which the number of controls can be minimized is by having a single control serve the purpose of two controls. This advantage in controls should be obtained by using as few electrical and mechanical elements as possible and the resulting combination of controls should be no more complex or difficult to fabricate and assemble than if two separate controls are used.

It is, therefore, an object of the present invention to provide an improved tone control in combination with an on-off control which is simple and inexpensive to manufacture, readily operable by the user and which does not add materially to the weight or bulkiness of the apparatus with which it co-acts to switch on or off, and to produce different characters of tone.

A further object of the present invention is to provide an improved inexpensive switch construction having a minimum number of parts that lends itself particularly well to fast assembly under mass-production methods.

Still another object of the present invention is to provide a simple improved tone control arrangement especially useful in small portable hearing apparatus.

The features of the present invention which are believed to be novel are set forth with particularity in the appended claims. The present invention itself, both as to its organization and manner of operation, together with further objects and advantages thereof may best be understood by reference to the following description taken in connection with accompanying drawings in which:

Figure 1 shows an improved combination tone control and on-off switch incorporated in a hearing aid circuit in accordance with the present invention;

Figures 2 through 5 show certain elements of the switch shown in Figure 1 in different operating positions thereof;

Figures 6 through 10 are diagrammatic representations of the different operating positions of certain elements shown in Figures 1 through 5 respectively;

Figure 11 shows an elevational view of a portion of a portable case having incorporated therein a tone control in accordance with the present invention;

2

Figure 12 shows a sectional view taken substantially on line 12—12 of Figure 1;

Figure 13 is a side view partly in section taken on the line 13—13 of Figure 1;

Figure 14 is one modification of the present invention as incorporated in a rotating cylindrical switch and

Figure 15 is another modification of the present invention as incorporated in a sliding switch.

In Figure 1 there is illustrated a hearing aid circuit incorporating an amplifier including electron discharge device 1, a second amplifier including electron discharge device 2 and an output stage including electron discharge device 3. The three amplifiers are connected in cascade to amplify signals from microphone 4 and impress such amplified signals on sound reproducing device 5 in linearly amplified form. A switch 6, described in detail hereinafter, for effecting on-off operation and tone control is interconnected with the amplifier.

As seen in Figures 1, 12 and 13, switch 6 has a fixed element 7 fixedly mounted on a base 8 by means of a pair of positioning lugs 9 and a mounting stud 10 which has one end threaded to receive a pair of nuts 11 which in turn provide secure mounting of stud 10 in the base 8. Located at a suitable angular distance from each other in fixed element 7, are contacts 12, 13, 14, 15 and 16, also shown in Figures 2 to 5 inclusive.

Positive drive between a rotating resilient contact member 16 and a rotating knob 17 is provided by an insulated pin 18 projecting from knob 17 and passing through the blade 19 of resilient contact member 16. A rounded embossment 20 formed in one end of the blade 21 of member 16 cooperates with the suitably spaced detent grooves 22, 23, 24, 25 and 26 in the fixed element 7 to positively locate the blades 27, 28, 29, 30 and 31 of the resilient contact member 16 in desired relation with the contacts 12, 13, 14 and 15 in the fixed element 7.

Insulated pin 18, in addition to providing the positive drive between the rotating resilient contact member 16 and the rotating knob 17, also cooperates with an arcuate shaped opening 32 in the fixed element 7 to confine rotation of the resilient contact member 16 and the rotating knob 17 within desired limits.

As seen in Figures 1, 12 and 13, a cam surface 33 is formed as a part of fixed element 7. In the first position of the switch 6, as illustrated in Figures 2 and 7, the blade 27 of resilient contact member 16 touches contact 12. In the second position, as illustrated in Figures 3 and 8, the

blade 27 touches contact 13 and the blade 28 touches contact 12. In the third position, as illustrated in Figures 1 and 6, the blade 27 touches contact 14, the blade 28 touches contact 13, and the blade 29 touches contact 12. In the fourth position, as illustrated in Figures 4 and 9, the blade 27 touches contact 15, the blade 28 touches contact 14, the blade 29 touches contact 13 and the blade 30 touches contact 12. In the fifth position, as illustrated in Figures 5 and 10, the blade 28 touches contact 15, blade 29 does not touch contact 14 because it has sufficient length to engage the cam surface 33 and thus be held out of engagement with contact 14, the blade 30 touches contact 13 and the blade 31 touches contact 12. The blades 27 and 28, being shorter in length than blade 29, pass by the cam surface 33 without being lifted thereby and consequently are allowed to touch contact 14 when they pass thereover. The blade 29, however, having greater length than the blades 27 and 28, cooperates with the cam surface 33 to be lifted clear of contact 14 as illustrated in Figure 5. The blades 30 and 31 also have sufficient length to reach the cam surface 33 but are limited in their rotation by the insulated pin 18 being confined within the arcuate shaped opening 32.

Figure 11 shows a portion of a portable case 34 having the combination on-off and tone control switch mounted therein. The rotating knob 17 has integrally formed projections 35 which extend slightly from portable case 34 for convenient manipulation by the finger of an operator and also has suitable indicia 36 for indicating to the operator the operating position of movable element 17.

The described switch is arranged to provide not only on-off action for the discharge devices 1, 2 and 3 but also several changes in tone. The various circuits of the amplifier are arranged together with the switch as follows for that purpose.

One terminal of filamentary cathode 37 is grounded and the other terminal is connected through filamentary cathode 38 to the positive terminal of source 49 of operating current therefor. Similarly one terminal of filamentary cathode 39 is grounded and the other terminal connected to positive terminal of source 49. The negative terminal of source 49 is connected to the contact 13 of switch 6 so that the negative terminal of source 49 is grounded through resilient contact member 16 and grounded contact 12 to make the amplifier operative in the second, third, fourth and fifth positions of the switch 6.

The input circuit of device 1 extends from its control electrode 41 through microphone 4 to the grounded terminal of cathode 37, whereby alternating potentials produced by microphone 4 are impressed between cathode 37 and control electrode 41. A grid leak resistance 42 is connected in shunt with microphone 4 to maintain control electrode 41 at proper operating potential with respect to cathode 37.

The output circuit of device 1 extends from its anode 43 through the serially connected load resistance 44 and bypassing condenser 45 to the grounded terminal of cathode 37. Space current for device 1 is provided by connection of a point between resistance 44 and condenser 45 to the positive terminal of a source 46 of operating potential, the negative terminal of source 46 being connected to ground through a relatively small biasing resistor 47 for device 3.

The screen electrode 48 of device 1 is main-

tained at a constant positive potential with respect to cathode 37 by connection of a bypassing condenser 49 between screen electrode 48 and the grounded terminal of cathode 37 and by connection of a resistance 50 between screen electrode 48 and the positive terminal of source 46.

The input circuit of device 2 extends from its control electrode 51, to the movable tap 52 of a volume control resistance 53 of which one terminal is grounded and the other terminal connected through coupling condenser 54 to anode 43, whereby any desired part of the alternating potential across resistance 44 may be impressed between control electrode 51 and cathode 38 of device 2 for further amplification.

The output circuit of device 2 extends from its anode 55 through a load resistance 56 to the positive terminal of source 46 and from the negative terminal of that source through resistance 47, ground, and filament 37 to cathode 38. Amplified alternating potential from device 2 therefore appears across resistance 56.

The screen electrode 57 of device 2 is connected to ground by a bypassing condenser 58 and to the positive terminal of source 46 through a resistor 59 so that it is maintained at a constant positive potential with respect to cathode 38.

The input circuit of device 3 extends from its control electrode 60 through a resistance 61 and biasing resistor 47 in series to ground. Coupling condenser 62 is connected between control electrode 60 of device 3 and anode 55 whereby the alternating potential across resistance 56 is impressed between control electrode 60 and cathode 39 of device 3 for further amplification.

The output circuit of device 3 extends from its anode 63 through the serially connected primary winding 64 of the transformer 65 and bypassing condenser 45 to the grounded terminal of cathode 39. Space current for device 3 is provided by connection of a point between primary winding 64 and condenser 45 to the positive terminal of the source 46 of operating potential.

The screen electrode 66 of device 3 is connected to ground by the bypassing condenser 45 and to the positive terminal of source 46 so that it is maintained at a constant positive potential with respect to cathode 39 and the signal potential across resistance 61 is amplified linearly by device 3 and appears across the secondary winding 67 of the transformer 65 which is connected to impress those voltages on the sound reproducing device 5.

In order to prevent any substantial alternating potential across the resistor 47, a bypass condenser 68 is connected from the positive terminal of source 46 to a point between resistors 61 and 47.

The tone of signals reproduced by sound reproducing device 5 is controlled by the switch which connects resistance 69 and capacitance 70 in the hearing aid circuit thus far described. For that purpose resistance 69 is connected between control electrode 41 and contact member 14 of switch 6 and capacitance 70 is connected between anode 43 and contact 15 of the switch. In general, the resistance 69, which may be connected by switch 6 in parallel circuit relationship to the piezo-

electric microphone 4, serves to reduce the intensity of low frequency signal components, and the capacitance 70 which may be connected by switch 6 between the electrode 43 and cathode 37 of discharge device 1 serves to reduce the intensity of high frequency signal components. For

this purpose, switch 6 serves to connect one terminal of resistance 69 to ground and also serves to connect one terminal of condenser 70 to ground. Different types of tone may be produced according to the four tonal positions of the rotary resilient contact member 16 shown in Figures 1, 3, 4 and 5. That is, the resilient contact member 16 is of such shape that in its counter-clockwise movement contact member 16 assumes positions whereby: (1) as in Figure 3 neither the resistance 69 nor the capacitance 70 is connected in the circuit, and neither the high notes nor the low notes are affected, and (2) as in Figure 1 the resistance 69 alone is connected in the circuit and high frequencies only are suppressed, and (3) as in Figure 4 both resistance 69 and capacitance 70 are connected in the circuit, and both some of the high and some of the low frequencies are suppressed and (4) as in Figure 5 the capacitance alone is connected in the circuit and high frequencies only are suppressed.

A modification of the previously described switch is shown in Figure 14—an exploded view of a cylindrical rotating switch. A rotating element 71 is shown without a finger-knob for sake of clarity. A fixed element 72, that may be fixedly mounted on a suitable base (not shown) by any conventional means, such as a mounting bolt passed through its mounting hole 73, coacts with element 71. A cam surface 74 is formed as part of the fixed element 72. A set of resilient blades 75, formed as a part of rotating element 71, coacts with a set of contacts 76 in the fixed element 72 to give the desired electrical connections.

A blade 77, one of the set of resilient blades 75, by reason of its length coacts with the cam surface 74 to be lifted clear of a contact 78 in much the same manner as blade 29 is lifted clear of contact 14 in the switch 6.

Another modification of the first described switch is shown in Figure 15. A sliding element 79 coacts with a fixed element 80. A cam surface 81 is formed as part of the fixed element 80. A set of resilient blades 82 formed as part of the sliding element 79 coacts with a set of contacts 83 in the fixed element 80 to give the desired electrical connections.

A blade 84, one of the set of resilient blades 82, by reason of its shape, coacts with the cam surface 81 to be lifted clear of contact 14 in the switch 6. The remaining blades of the set of resilient blades 82 have a U-shaped part 86 incorporated therein in a position that allows these blades to clear the cam surface 81 and therefore all such blades touch contact 85 as they pass thereover.

The cam surface 81, being located between the fixed contact 85 and the sliding element 79 results in a switch having short, stubby resilient blades 82 that furnish positive wiping action across the fixed contacts 83 and fulfills all requirements for a short and compact switch.

The rotating cylindrical switch shown in Figure 14 has long flexible blades ideally suited for operation with a knob of small diameter.

The switch 6, shown in Figures 1, 12 and 13, although somewhat similar in arrangement to the modification shown in Figure 14 has its resilient contact member 16 formed in such manner that all the blades can easily withstand the bending that they are normally subjected to and consequently this results in a durable switch.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. An electrical switch comprising a pair of resilient movable contacts, a pair of fixed contacts disposed in the path of said movable contacts, and a cam disposed adjacent one of said fixed contacts, said cam being arranged to operate on only one of said movable contacts, whereby said one movable contact is prevented from engaging said one fixed contact.

2. A rotary switch comprising a rotatable member bearing a pair of movable resilient radial contacts, the radial length of one of said contacts being greater than that of the other of such contacts, a pair of fixed contacts disposed in the path of said radial contacts, and a cam disposed adjacent one of said fixed contacts and in the path of said one movable contact only, whereby said one movable contact is prevented from engaging said one fixed contact.

3. A rotary switch comprising a first cylindrical structure bearing a pair of movable resilient axial contacts, the axial length of one of said movable contacts being greater than that of the other of such contacts, a second cylindrical structure coaxial with said first structure and bearing a pair of fixed contacts arranged in the path of said movable contacts, and a cam disposed adjacent one of said fixed contacts and in the path of said one movable contact only, whereby said one movable contact is prevented from engaging said one fixed contact.

BYRON R. CRISWELL.
